UNITED STATES PATENT OFFICE.

HIRAM B. DECIUS, OF BOISE, IDAHO.

ICE-CREEPER.

1,055,144.

Specification of Letters Patent.

Patented Mar. 4, 1913.

Application filed November 29, 1911. Serial No. 662,994.

To all whom it may concern:

Be it known that I, HIRAM B. DECIUS, a citizen of the United States, residing at Boise, in the county of Ada and State of Idaho, have invented new and useful Improvements in Ice-Creepers, of which the following is a specification.

The invention relates to creeping devices and more particularly to the class of ice 10 creeping foot wear.

The primary object of the invention is the provision of a device of this character in which the foot of the wearer will be prevented from slipping upon ice, sleet or 15 wet surfaces when treading thereon, thus assuring a positive footing on such surfaces, thereby avoiding accidents resulting from falls, the device being especially useful to workmen in artificial ice plants, log 20 camps, breweries, and shingle roofers, as well as pedestrians.

Another object of the invention is the provision of a device of this nature which enables a person to walk upon slippery surfaces and especially in hazardous places.

The device is adapted to be applied to the shoe of the wearer and may be made in a variety of sizes so as to be worn by 25 grown persons, children or youths.

A further object of the invention is the provision of a device of this character which is simple in construction, readily and easily applied to the foot or shoe of the wearer, reliable and efficient in its purpose, strong, 30 durable and inexpensive in manufacture.

With these and other objects in view the invention consists in the construction, combination and arrangement of parts, as will be hereinafter more fully described, illustrated in the accompanying drawings, and 35 pointed out in the claim hereunto appended.

In the drawings, Figure 1 is a perspective view of a device, the same being especially useful for roofers. Fig. 2 is a bottom 40 plan view thereof. Fig. 3 is a vertical longitudinal section view through the device.

Similar reference characters indicate corresponding parts throughout the several views in the drawings.

50 In Figs. 1, 2 and 3 of the drawings there

is shown an anti-creeping device which comprises a sole 18, instep 19 and a hollow heel 20. Rising from the sole at the toe portion thereof and suitably fixed thereto is a tip 21 in which is adapted to be engaged the toe portion of the shoe of the wearer, while fixed to and rising from the heel end of the device is a heel boxing 22, which receives the heel portion of a shoe, the heel proper thereof being engaged in 60 the hollow heel 20. Fixed to and extending forwardly from the heel boxing 22 is a pair of fastening straps 23, one of which carries the usual buckle 24 to be engaged by the other strap and in this manner the device 65 is fastened about the shoe when on the wearer. Fixed to the inner side edge of the sole 18, instep 19 and a portion of the heel 20 and rising therefrom, is a side section 25, in which are fixed a plurality of 70 spikes or pins 26, while fixed in the sole 18 and heel 20 are a plurality of spikes or pins 27 similar to the spikes or pins 26, thus it being seen that when treading upon a slippery surface the pins or spikes on the 75 sole and heel of the device will prevent the slipping of the wearer. Now when the device is thrown sidewise the side section carrying the pins 26 will grip the slippery surface to prevent the slipping of the foot of 80 the wearer, this position being assumed by roofers when at work. It will be apparent that the wearer will be assured a positive footing when walking, standing or kneeling upon a slippery surface.

85 What is claimed is:

A device of the class described comprising a sole portion having a tip instep and heel, spikes mounted in and projecting outwardly from the heel and sole portion, a 90 side section fixed to the outer side edge of the sole, instep and heel and spikes mounted in and projecting outwardly from the said side sections throughout the area thereof.

In testimony whereof I affix my signature in presence of two witnesses.

HIRAM B. DECIUS.
